UNITED STATES PATENT OFFICE.

SABELLA GERTRUDE DOHERTY, OF NEW YORK, N. Y.

MIRROR DECORATING AND ILLUMINATING DEVICE.

SPECIFICATION forming part of Letters Patent No. 744,507, dated November 17, 1903.

Application filed June 12, 1902. Serial No. 111,338. (No model.)

To all whom it may concern:

Be it known that I, SABELLA GERTRUDE DOHERTY, a citizen of the United States, and a resident of the city of New York, borough of Manhattan, in the county and State of New York, have invented a new and Improved Mirror Decorating and Illuminating Device, of which the following is a full, clear, and exact description.

10 The invention relates to decorative lighting by electric lamps of the incandescent type; and its object is to provide a new and improved illuminated garland for use on mirrors, walls, interior and exterior balconies, 15 and other objects and arranged to heighten the ornamental effect of the object as well as provide the desired illumination of the surrounding objects.

The invention consists of novel features 20 and parts and combinations of the same, as will be more fully described hereinafter and then pointed out in the claims.

A practical embodiment of the invention is represented in the accompanying drawings, 25 forming a part of this specification, in which similar characters of reference indicate corresponding parts in all the views.

Figure 1 is a face view of the improvement arranged for decorating a mirror. Fig. 2 is 30 an enlarged transverse section of the same on the line 2 of Fig. 3. Fig. 3 is a sectional front elevation of the same on the line 3 3 of Fig. 2. Fig. 4 is a rear face view of the garland, and Fig. 5 is a face view of the reinforcing-wire of the garland-body.

The improvement, as shown in the drawings, is in the form of a garland of roses in relief, and consists, essentially, of a body A of a suitable plastic material molded, pressed, or 40 otherwise produced and reinforced at the back by a doubled-up wire B, having terminal hooks B', adapted to be hooked onto screw-eyes, staples, or like supporting devices C, secured on the frame of the mirror or other 45 object D to be decorated. As shown in Fig. 1, three garlands are employed for decorating the mirror at the upper end below the head D', the central garland being suspended at its upper end from a screw-eye C and hanging 50 down in front of the glass, at the middle thereof, while the other garlands extend from the same or separate eyes C and extend down-

ward and outward over the glass in a graceful curve to the sides of the mirror-frame to engage with their hooks B' eyes C on the 55 frame; but it is evident that the arrangement of a single or a plurality of garlands may be varied according to the object to be decorated to suit existing conditions.

The wire B is embedded in the plastic material and is formed between its ends with loops B², extending in the walls of transverse openings A', formed in the body A and central with sundry or all of the roses in the garland. Each of the openings A' is adapted to 60 receive a socket E for the bulb E' of an incandescent electric lamp projecting centrally from the roses, at the front thereof, so that when the electric lamps are lit the light appears emanating from the roses' center, thus 65 producing a highly-ornamental decorative effect.

The insulated conducting-wires F for the electric lamps of a garland extend along the back thereof and pass through insulated 75 tubes G, held on the head D' of the mirror or other object D, so that convenient access is had to the wires for making connection with the general feed-wires or for making repairs to the sockets, &c.

The loops B² strengthen the walls of the socket-openings A' to securely hold the lamp-sockets E in place.

Suitable switches (not shown) are connected with the feed-wires to control the lighting 85 and extinguishing of the lamps in the garlands. The hooks or wires at the connecting point at the head D' are hidden by a suitable ornament H, as indicated in Figs. 1 and 2.

It is understood that by the arrangement 90 described the garlands can be readily attached to or removed from the object, and convenient access is had to the wires and the parts of the electric lamps for making repairs or alterations whenever deemed necessary, without disturbing the mirror.

The garlands can be cheaply manufactured, and when in use heighten the ornamental effect of the object decorated, as well as provide the desired illumination of the frame in 100 which the object is located.

It will be seen that by the arrangement described it is not necessary to bore holes in the glass to make connections between the

electric lamps and the feed-wire located behind the mirror, as heretofore practiced.

Having thus described my invention, I claim as new and desire to secure by Letters 5 Patent—

1. The combination with a mirror provided with a head having insulated tubes arranged therein, of the illuminating device therefor arranged in front of the upper part of the reflecting-surface of the mirror and consisting of a body having means for suspending the same from the mirror-frame, the body having spaced transverse apertures, electric-lamp bulbs held in said apertures and projecting 15 from the front of the body, and conducting-wires at the back of the body and connected with the lamps, the said wires extending upward and passing through the insulated tubes in the head of the mirror as set forth.
2. The combination with a mirror, provided with a head having openings therein of the illuminating device therefor arranged in front of the reflecting-surface of the mirror, and consisting of a body having hooks at its 25 ends for engaging supports on the mirror-frame, the said body having spaced transverse apertures, sockets removably held in the apertures, lamp-bulbs fitting in the said sockets and projecting from the front thereof, and conducting-wires back of the body between the same and the mirror and connected 30 with the said sockets, the said wires extending upward and passing through the openings in the head of the mirror, as set forth.

3. The combination with a mirror having a 35 series of openings passing through the head of the frame, of the illuminating device therefor, arranged in front of the reflecting-surface of the mirror and consisting of a central body suspended from the head of the mirror-frame and hanging in front of the upper portion of the reflecting-surface of the mirror, and side bodies shaped at their upper portions to fit against the sides of the central body at the top thereof, the said side bodies 40 being also suspended from the head of the mirror-frame and extending from the central body to the sides of the mirror-frame, the said bodies having spaced transverse apertures, electric-lamp bulbs held in said apertures and projecting from the front thereof, conducting-wires at the back of the said bodies and connected with the said lamps, the said wires extending upward and passing through the openings in the head of the mirror, and a downwardly-projecting member 45 connected with the head of the mirror-frame, and extending in front of the suspending devices for the said bodies and the upper part 50 of the conducting-wires, as set forth.

In testimony whereof I have signed my name to this specification in the presence of two subscribing witnesses.

SABELLA GERTRUDE DOHERTY.
